ASSIGNORS TO BURSON MANUFACTURING COMPANY, OF ROCKFORD, ILLINOIS, A
CORPORATION OF ILLINOIS.

KNITTING-MACHINE.

1,163,341.

Specification of Letters Patent. Patented Dec. 7, 1915.

Application filed April 19, 1915. Serial No. 22,463.

To all whom it may concern:

Be it known that we, WILLIAM E. HINCHLIFF and CHARLES W. ANDERSON, citizens of the United States, residing at Rockford, in the county of Winnebago and State of Illinois, have invented certain new and useful Improvements in Knitting-Machines, of which the following is a specification:

This invention relates in general to knitting machines of the "straight" type and has more particular reference to the construction of the needle beds thereof.

In knitting machines of this type which comprise rows of parallel needles and needle beds, it has been found most practical to construct the needle beds of alternately disposed division-wall plates and needle supporting or bed plates, all suitably bound together so as to form a series of individual 20 needle compartments each adapted to support and guide a needle. As a result of continual reciprocation of the needles, the bearing surfaces of these plates become worn and grooved, thereby necessitating renewal of the plates. In view of the large 25 number of plates that are comprised in a needle bed, it is obvious that renewal or replacement of the bed plates is a laborious and expensive operation, especially in view 30 of the fact that the entire needle bed structure must be taken apart and reassembled.

The primary object of our invention is the provision of a needle bed so constructed that the wear occasioned by the reciprocation of the needles will be reduced to a minimum and which, when eventually worn by long usage can be readily adjusted to provide new bed surface or repaired without disassembling the needle bed structure.

Another object of our invention is to provide a needle bed wearing surface consisting of a single, hardened member which serves as the supporting bed for all of the needles in one row, and which may be adjusted to present new surfaces for the needles.

Other objects and many attendant advantages of our invention will be more fully understood as the invention becomes better understood by reference to the following description when considered in connection with the accompanying drawings, wherein,—

Figure 1 is a fragmentary plan view of a needle bed structure embodying our inven-

tion, part of the division plates, bottom plates and needles being removed; Fig. 2 is a transverse sectional view through the needle bed shown in Fig. 1; and Fig. 3 is a fragmentary perspective view illustrating the manner in which the needle bed-surface member is associated with the division and bottom plates, the division and bottom plates being separated to more clearly show the construction.

By reference to the drawings in which we have illustrated only so much of a needle bed structure of a straight row knitting machine as is necessary to convey a clear understanding of our invention, it will be observed that the bed structure comprises supporting rods 4, upon which are mounted a series of alternately disposed division or wall plates 5 and bottom plates 6 together forming a series of individual needle compartments designated by reference character 7. Needles 8, one disposed in each of said compartments, are projected from the upper ends of the compartments to perform the knitting operation by means of needle-actuating jacks 9, operated by the usual cam (not shown) and controlled by jack-levers 10 actuated from a pattern cylinder of conventional or preferred construction.

Heretofore, it has been the practice to slidably mount the needles directly on the top surface of the plates 6 against which they are held by the springs 14. As a result of this construction, the said plates being merely unhardened sheet steel stampings, and it being impractical to harden the bearing surfaces of these stampings, said bearing surfaces become worn and grooved by reciprocation of the needles. As soon as the plates become worn to any considerable extent it becomes necessary to disassemble the entire bed structure and replace the worn plates by new ones. By our invention we have greatly improved the bed structure so that wear of the needle bed surface is reduced to a minimum and the machine may be run easier and with less frictional resistance during a much longer period of operation than has been formerly possible.

We accomplish the several objects and advantages above mentioned by providing a single adjustable member which forms the 105 needle bed surfaces for all the needles in one

row in a machine. This member is in the form of an elongated relatively thin, hardened, steel plate designated by reference character 15, passing through apertures 16 in the division plates 5 and seated in recesses 17 in the bottom plates 6 in such manner that one of the flat sides of said member forms the bed surface for all the needles in the row. It is obvious that such a hardened 10 steel needle bed surface will permit the needles to be very efficiently operated during a long period of operation. When, however, the surface upon which the needles reciprocate does become worn, the bed plate 15 may 15 be moved longitudinally a distance equal to the width of one of the division plates 5 to thereby bring the unused surfaces of the bed plate from beneath the division plates into the needle compartments and provide 20 new bearing surfaces for the needles. It will be here noted that this renewal of the needle bed surface is effected without dis- 25 assembling or disturbing the structure of the machine. When the renewed bearing surfaces of the bed plate 15 have become worn after a period of operation, the plate may be further adjusted to provide new bearing surfaces by withdrawing the plate lengthwise from the bed structure, reversing 30 the plate, and replacing it in operative position with its unused flat side uppermost in position to serve as the bed surface for the needles. It is obvious, of course, that in order to renew the needle bed surface by this 35 last method, the needles must first be removed and then replaced after the bed plate has been replaced. The needles, however, may be very easily withdrawn longitudinally from the needle compartments 40 and replaced without difficulty and without disturbing any of the permanent mechanical structure.

We claim:

1. In a knitting machine, a needle bed including a plate upon which a series of spaced needles slide, the plate being adjustable longitudinally of the bed to present new bearing surfaces for the needles.

2. In a knitting machine, a needle bed including a plate upon which a series of needles are slidably mounted, the plate being reversible so that any portion of its sides

may be used as bed surface upon which the needles may slide.

3. In a knitting machine, a needle bed 55 comprising a plurality of individual needle compartments, the bottoms of which are formed by a single member provided with a needle supporting surface upon which the needles slide, said member being adjustable 60 to present new needle-bearing surfaces to said compartments.

4. In a knitting machine, a needle bed comprising bottom plates, division plates, and a plate extending transversely through 65 the division plates and resting upon said bottom plate and forming a needle bearing surface above the bottom plates upon which surface the needles reciprocate.

5. In a knitting machine, a needle bed 70 comprising spaced division plates, and a plate extending transversely through the division plate forming bearing surfaces intermediate said plates upon which needles interposed between said division plates may 75 slide reciprocably.

6. In a knitting machine, a needle bed comprising a series of individual needle compartments including a removable member provided with a hardened surface forming the bed surface upon which needles located in said compartments slide reciprocably.

7. In a knitting machine, a needle bed comprising a series of bottom plates, and a 85 hardened needle-supporting plate extending longitudinally of the bed and upon which the needles reciprocate, the top of the bed plates being recessed to receive said hardened plate.

8. In a knitting machine, a needle bed comprising spaced division plates having apertures extending transversely therethrough and arranged in alinement, and a plate passing through said apertures forming 95 the needle-bearing surfaces upon which needles disposed between the division plates reciprocate.

WILLIAM E. HINCHLIFF.
